APPARATUS FOR TREATING PISTONS

Harold P. Phillips, Hastings, Mich., assignor to
Hastings Manufacturing Company, Hastings,
Mich., a corporation of Michigan

Application April 23, 1942, Serial No. 440,236

7 Claims. (Cl. 153—32)

This invention relates to improvements in apparatus for treating pistons.

The main objects of this invention are:

First, to provide an apparatus for treating pistons of internal combustion engines and the like which enables the use of a worn piston or a standard size piston in a rebored cylinder.

Second, to provide an improved apparatus for treating pistons by means of which a longitudinal area of a piston skirt may be effectively offset to the desired degree without inducing or producing in the piston distortion stresses which might result in the ultimate fracturing of the piston wall or change in its shape.

Third, to provide an apparatus for treating pistons which may be used successfully by persons other than highly skilled mechanics.

Fourth, to provide an apparatus having these advantages in which the amount of offset in the piston skirt can be accurately determined.

Fifth, to provide an apparatus for performing a method of treating pistons which may be successfully practiced on a large scale and with uniform results.

Objects relating to details and economies of the invention will appear from the description to follow. The invention is defined in the claims.

A preferred embodiment of the invention is illustrated in the accompanying drawings, in which:

Fig. 1 is a perspective view of an apparatus embodying the features of my invention with a piston in position in the machine, the parts being shown in actuated position.

Fig. 2 is a fragmentary perspective view showing further details of the apparatus.

Fig. 3 is a side elevation of a piston treated by the apparatus.

Fig. 4 is an enlarged fragmentary view in section on line 4—4 of Fig. 6 with a piston in operative position at the end of the completion of the work thereon.

Fig. 5 is a fragmentary view showing further details of the actuating means.

Fig. 6 is an enlarged detail section on a line corresponding to line 6—6 of Fig. 4.

The embodiment of my invention illustrated comprises a table or bench 1 mounted upon suitable legs or standards 2. At one end of the table I mount a pair of laterally spaced work supports 3, these work supports having angular work engaging portions 4 with a series of notches 5 therein. These work supports are adapted to receive a piston 6 to support the same at laterally disposed zones longitudinally of the piston, the work sup-

ports extending substantially the full length of the piston skirt.

The table is provided with a laterally disposed portion 7 at one end having an upright web 8 thereon to the sides of which the plates 9 are bolted to provide an upwardly facing groove-like holder. The upper face or bottom 10 of this holder is inclined as shown in Fig. 6.

10 The anvil or outer die member 11 has a downwardly facing longitudinal groove-like recess 13 therein receiving the upper edge of the adjusting member 14 which has an inclined bottom 15 complementary to the inclined surface 10 of the holder so that by adjusting the member 14 longitudinally in the holder, the outer die or anvil member 11 is raised and lowered. This member 11 has a concavely curved face 16 with a series of spaced notches 17 in the edges thereof. The purpose of these notches will be pointed out as the description proceeds.

15 The adjusting member 14 is adjusted by the screw 18 having a finger-piece 19 at its outer end, the screw being threaded through the bracket 20 and having a swivel connection to the member 14, the connection not being shown. This screw has an indicia member 21 having a micrometer scale indicating thirty-thousandths of an inch. An index finger or pointer 22 is mounted on the screw and adjustably associated with the 20 scale or gauging indicia.

25 In adjusting, the work is laid upon the supporting members and the screw adjusted until the anvil member is brought into contact with the skirt of the piston. The index finger is then 30 adjusted preferably to a top position where it can be easily viewed and the screw backed off to the desired degree. For example, if it were desired to offset the piston thirty-thousandths of an inch, the thumb piece would be given one complete rotation. The inner die member or thrust member 23 is then positioned within the piston in opposed relation to the anvil die member and the thrust member 24 adjusted to bring its arm 25 into overhanging relation to the die member 23. This arm 25 is provided with a spherical contact member 26 which coacts with a socket 27 in the die member 23 so that there is, in effect, a ball and socket thrust engagement between these members.

35 The thrust member 24 is supported in a slot 28 in the bracket or frame-piece 29 both for horizontal movement to bring the arm 25 into and out of operative position and also to permit vertical movement for applying the actuating thrust to the die member. To this end, I associate the

actuating lever 30 with the arm 31 on the lower end of the thrust member.

The lever 30 is pivoted at 32 on a pair of spaced brackets or ears 33, the pivot 32 being selectively engageable with the vertical series of holes 34 5 in these ears. It will be noted that the lever engages the arm 31 very close to the pivot so that a very powerful lever action results. This permits the use of a relatively light weight 35 for actuating the lever. The weight is preferably used so as to secure a uniform thrust or actuation. The weight is provided with eyes 36 which are slidable on the lever to and from its pivotal point. Lateral movement of the lever is prevented by a pair of spaced upwardly projecting arms 37 and 38 disposed near the outer end of the table. A threaded stop 39 provided with a knurled finger-piece 40 is disposed near the inner end of the lever to limit the downward movement thereof or to stop its downward movement during the forming operation.

In adjusting the work, the weight 35 is preferably moved inwardly on the lever. In placing work in the machine or apparatus, the thrust member is retracted to the position shown in Fig. 2, the work placed on the supports, the inner die member or thrust die member positioned within the work, and the thrust member 24 is then moved horizontally to position its arm 25 above the die member so that when actuated the spherical thrust member 26 will engage the socket 27.

It will be noted that the burners 41 are positioned so that the flames thereof are directed upwardly between the downwardly diverging inner sides 42 of the supports 3 and at either side of the outer or anvil die member 11. The series of notches 5 in the support members and the corresponding series of notches 17 in the outer or anvil die member 11 facilitate the heating of the portion of the piston skirt at and between the supported zones thereof. The burners are provided with a control valve 43.

With the work in position and the outer or anvil die member properly backed off from the work to the desired degree, as has been described, the burners are lighted and the weight moved outwardly to operative position. As soon as the metal becomes sufficiently heated, the actuating lever, actuated through its weight, will offset the portion of the piston between the supports as indicated at 44 until the offset portion contacts the outer or anvil die member.

In order that the operator may better observe the offsetting action or the heating action, I provide a graduated scale 45 with which I associate the pointer 46 which is pivoted at 47. This pointer has a counterweight 48 which is, however, merely intended to counterbalance the pointer on its pivot. This pointer is operatively connected to the actuating lever by the link 49 which is adjustably connected to the outer end of the actuating lever by the thumb screw 50 arranged through the slide 51 receiving the link, the link being hooked to engage over the pointer. It will be observed that the pointer end of the pointer has a very substantial throw for convenience in observation or reading.

When the apparatus is set up ready for operation, the link is adjusted so that the pointer indicates zero on the scale of 45. As soon as the lever begins to travel downwardly as results from the softening of the metal, the pointer begins to swing upwardly as indicated in Fig. 1 and if this movement is too rapid—that is, if

it indicates overheating of the work, the operator can adjust the valve 43 or close it entirely. Another safety factor is provided in the adjustable stop 38 which in the event the operator is of the opinion that the work has been sufficiently heated or is becoming excessively heated, he can adjust the screw to stop the action of the lever. These features are aids to avoid injury to the work and as a matter of general convenience for use of the apparatus. The lever is preferably longitudinally slotted, as shown in Fig. 2, to embrace the upright 45, thus providing further support for the lever.

While the method may be very satisfactorily carried out with the apparatus illustrated, it may be practiced by other apparatus in which the separate steps are mainly manually performed.

I have illustrated and described my invention in an embodiment which I have found highly satisfactory and one which enables the very rapid and practical treatment of pistons without subjecting the metal thereof to undesirable stresses as frequently results from the variously practiced hammering and distortion methods. By the use of this apparatus very little grinding or finishing is required as the resizing or offsetting is very uniform and the degree of offsetting may be controlled to a thousandth of an inch.

I have not attempted to illustrate or describe the various modifications and adaptations which I contemplate as it is believed that this disclosure will enable those skilled in the art to embody or adapt my invention as may be desired.

Having thus described my invention, what I claim as new and desire to secure by Letters Patent, is:

1. In an apparatus of the class described, the combination of a pair of laterally spaced work supports, said work supports being disposed to supportingly engage a piston along spaced lines extending longitudinally of the piston, a die member support disposed below and centrally relative to said work supports and having an upwardly facing groove-like holder provided with an inclined bottom, an adjusting member disposed in said holder and having an inclined bottom complementary to the inclined bottom of said holder, an outer die member having its die face disposed between and below the lines of supporting engagement of said work supports with the piston, said die member being grooved to receive said adjusting member, an adjusting screw for said adjusting member provided with micrometer indicia and associated pointer, the adjustment of said adjusting member moving said die member towards or from the work on said work supports, an inner die member adapted to be disposed within the piston in opposed relation to said outer die member, an adjustably mounted thrust member for said inner die member to move the inner die member towards the outer die member, said thrust member and inner die member having ball and socket coengaging portions, an actuating lever coacting with said thrust member, an actuating weight adjustable on said actuating lever, a movement indicator for said actuating lever comprising a pointer and associated indicia, said pointer being detachably connected with said actuating lever, said outer die member being spaced from said work supports to expose spaced areas of the piston extending longitudinally thereof, burners disposed on opposite sides of said outer die member to deliver heat onto said exposed

areas of the piston, and manual means for controlling said burners.

2. In an apparatus of the class described, the combination of a pair of laterally spaced work supports, said work supports being disposed to supportingly engage a piston along spaced lines extending longitudinally of the piston, a die member support disposed below and centrally relative to said work supports and having an upwardly facing groove-like holder provided with an inclined bottom, an adjusting member disposed in said holder and having an inclined bottom complementary to the inclined bottom of said holder, an outer die member having its die face disposed between and below the lines of supporting engagement of said work supports with the piston, said die member being grooved to receive said adjusting member, an adjusting screw for said adjusting member provided with micrometer indicia and associated pointer, the adjustment of said adjusting member moving said die member towards or from the work on said work supports, an inner die member adapted to be disposed within the piston in opposed relation to said outer die member, an adjustably mounted thrust member for said inner die member to move the inner die member towards the outer die member, said thrust member and inner die member having ball and socket coengaging portions, an actuating lever coacting with said thrust member, an actuating weight adjustable on said actuating lever, said outer die member being spaced from said work supports to expose spaced areas of the piston extending longitudinally thereof, burners disposed on opposite sides of said outer die member to deliver heat onto said exposed areas of the piston, and manual means for controlling said burners.

3. In an apparatus of the class described, the combination of a pair of laterally spaced work supports having angular notched work-engaging edges and downwardly diverging inner sides, said work supporting edges being disposed to engage a piston along spaced lines extending longitudinally of the piston, a die member support disposed below and centrally relative to said work supports and having an upwardly facing groove-like holder provided with an inclined bottom, an adjusting member disposed in said holder and having an inclined bottom complementary to the inclined bottom of said holder, an outer die member having its die face disposed between and below the lines of supporting engagement of said work supports with the piston, said die member being grooved to receive said adjusting member and having a curved face and notches in its sides opening to said face, an adjusting screw for said adjusting member provided with micrometer indicia and associated pointer, the adjustment of said adjusting member moving said die member towards or from the work on said work supports, an inner die member adapted to be disposed within the piston in opposed relation to said outer die member, means for applying pressure to said inner die member to move the inner die member towards the outer die member, and burners disposed on opposite sides of said outer die member to deliver heat to exposed areas of said piston between the downwardly diverging walls of said support members and on both sides of said outer die member, said notches in said supports and outer die member facilitating the distribution of heat to the piston, and manual means for controlling said burners.

4. In an apparatus of the class described, the

combination of a pair of laterally spaced work supports, an outer die member having its face disposed between and spaced from the work supports, a die member support having an inclined supporting surface, an adjusting member for said outer die member mounted on said support and having an inclined surface opposed to the inclined surface of said support, an adjusting screw for said adjusting member provided with indicia and associated pointer, the adjustment of said adjusting member moving said die member towards or from the work on said work supports, an inner die member adapted to be disposed within the piston in opposed relation to said outer die member, a thrust member for said inner die member to move the inner die member towards the outer die member, an actuating lever coacting with said thrust member, an adjustable actuating weight for said actuating lever, a manually adjustable stop for said lever, a movement indicator for said actuating lever comprising a pointer and associated indicia, said pointer being detachably connected with said actuating lever, and burners disposed on opposite sides of said outer die member to deliver heat to exposed areas of said piston between the said support members and on both sides of said outer die member.

5. In an apparatus of the class described, the combination of a pair of laterally spaced work supports, an outer die member having its face disposed between and spaced from the work supports, a die member support having an inclined supporting surface, an adjusting member for said outer die member mounted on said support and having an inclined surface opposed to the inclined surface of said support, an adjusting screw for said adjusting member provided with indicia and associated pointer, the adjustment of said adjusting member moving said die member towards or from the work on said work supports, an inner die member adapted to be disposed within the piston in opposed relation to said outer die member, a thrust member for said inner die member to move the inner die member towards the outer die member, an actuating lever coacting with said thrust member, an adjustable actuating weight for said actuating lever, and burners disposed on opposite sides of said outer die member to deliver heat to exposed areas of said piston between the said support members and on both sides of said outer die member.

6. In an apparatus of the class described, the combination of a pair of laterally spaced work supports having notched work-engaging portions disposed to engage a piston along spaced areas extending longitudinally and exteriorly of the piston, an anvil die member disposed between and spaced from said work-engaging portions and having a series of notches in its sides opening to its face, a die member support having an inclined supporting surface, an adjusting member for said anvil die member mounted on said support and having an inclined surface opposed to the inclined bottom of said support, an adjusting screw for said adjusting member provided with indicia and associated pointer, the adjustment of said adjusting member moving said die member towards or from the work on said work supports, a thrust die member adapted to be disposed within the piston in opposed relation to said anvil die member, means for actuating said thrust die member towards said anvil die member, and burners disposed on opposite sides of said thrust die member to deliver heat onto the exposed areas of the piston between the said support members and on

both sides of said anvil die member, said notches in said supports and anvil die member facilitating the distribution of heat to the piston.

7. In an apparatus of the class described, the combination of a pair of laterally spaced work supports having notched work-engaging portions disposed to engage a piston along spaced areas extending longitudinally and exteriorly of the piston, an anvil die member disposed between and spaced from said work-engaging portions and having a series of notches in its sides opening to

its face, means for adjusting said anvil die member relative to said work supports, a thrust die member opposed to said anvil die member, means for actuating said thrust die member towards said anvil die member, and means disposed on opposite sides of said anvil die member for delivering heat between the said supports and on both sides of said anvil die member, said notches in said supports and anvil die member facilitating the distribution of heat to the work.

10. HAROLD P. PHILLIPS.
